UNITED STATES PATENT OFFICE.

MARTIN ZWICKE, OF NEW YORK, N. Y., ASSIGNOR TO I. B. KLEINERT RUBBER COMPANY, OF NEW YORK, N. Y., A CORPORATION OF NEW YORK.

GARMENT-PROTECTOR.

1,351,982.

Specification of Letters Patent.

Patented Sept. 7, 1920.

Application filed September 18, 1919. Serial No. 324,356.

To all whom it may concern:

Be it known that I, MARTIN ZWICKE, a citizen of the United States, and a resident of the city of New York, county of Queens, 5 and State of New York, have invented a certain new and useful Improvement in Garment-Protectors, of which the following is a specification.

This invention relates to a moisture proof 10 garment usually worn by infants as a protective covering over the ordinary absorbent diaper, and the object of this invention is to provide a garment of this character so arranged that it may be put on and taken off 15 rapidly, and will at all times effectively prevent the egress of moisture and protect the child's outer garments properly. By means of its particular construction and material, it provides a means for protecting 20 the child's damp diaper from contact with the floor, should the child be playing there, whereby possibilities of the child contracting colds or sickness is prevented.

A further object of this invention is to 25 provide a seamless form of garment protector which may be formed from a single piece of material, and which will properly and comfortably fit the wearer affording at 30 all times a maximum amount of protection. While I have referred to the garment herein as particularly adaptable as "baby pants" it will be understood that the same may be made in various sizes and forms and used for protective purposes generally.

35 With these objects and other objects which may hereinafter appear, in view, I have devised the particular arrangement of parts hereinafter set forth and more particularly pointed out in the claims appended 40 hereto.

Reference is to be had to the accompanying drawings, forming part hereof, in which

45 Figure 1 is a face view of the blank from which the garment is formed;

Fig. 2 is a front elevation of the garment protector produced therefrom, and

Fig. 3 is a side elevation of the same.

Throughout the various views of the 50 drawings, similar reference characters designate similar parts.

In the preferred embodiment of the invention as disclosed in the accompanying drawing, 1 indicates the blank from which the 55 garment is formed. This blank is pref-

erably made of thin rubber or of any material which will be impervious to moisture, or, if the garment is not to be used for protective purposes, the material used in its construction may be an ordinary textile ma- 60

In the drawing, I have shown the blank formed in a generally oval contour. This is the preferred design, although the blank 65 may be made circular in contour or in various forms and sizes to suit varying requirements.

The blank 1 is formed with openings 2, one of these openings being placed on each side of the transverse center line 3 of the 70 blank.

These openings 2 form the leg openings of the garment and as shown are preferably made oval in outline, the longitudinal axis of each of these openings extending at an 75 angle to the longitudinal center line 4 of the garment blank, and likewise at an angle to the transverse center line 3.

The leg openings 2 may be varied in outline to suit varying requirements, the dotted 80 lines 5 indicating another form of opening which is in the form of an elongated slot.

It is also to be noted that the leg openings are placed at one side of the central longitudinal line 4 of the blank or nearer to the side 85 edge 6 than to the edge 7.

The edge 6 of the blank is at the front of the garment when the same is constructed, while the edge 7 forms the rear thereof. Thus it will be seen that more material is 90 found between the openings 2 and the edge 7, thus producing the requisite fullness at the rear of the garment, as disclosed in Fig. 3.

To construct the garment, the outer edge 95 of the blank is drawn together or shirred as at 8 to cause the blank to assume a bag-like contour. To allow an expansion of the waist opening thus formed a strip of flat, 100 expansible material 9, such as elastic material, is secured by lines of stitching 10 over the inner face of the shirring 8. This flat strip of elastic material, being placed on the inner side of the garment, or in other words, that side of the garment nearest to 105 the wearer's body, acts as a covering or cushion for the shirring 8, and any discomfort that might be caused to the wearer by contact with the thicknesses of material produced by the shirring is prevented, as 110

this strip provides a flat, wide and even contacting surface.

The leg openings 2 are also provided with contracting means such as shirring 11, and 5 are likewise provided with the flat, unshirred expansible strips or bands 12 which are secured over the inner face of the shirring by stitches 13. These bands 12 are in 10 all respects similar to the band or strip 9 at the waist opening of the garment.

When the garment is being put on or taken off, the elasticity of the expansible strips 9 and 12, surrounding the openings in the garment, together with the shirring 15 adjacent these openings, permits a ready distortion of these openings and when the garment is in place a perfect fit at these points is afforded so that egress of moisture at these points is effectively prevented.

20 The manner of providing an expansible and contractible means at the openings in the garment as by the utilization of the flat expansible strips and shirrings is the preferred manner of forming the garment, although it will be apparent that any 25 contracting means for these openings, such as by tapes or draw strings may be used.

It will also be noted that the particular 30 position of the leg openings in the blank 1, provides, when the garment is completed, the proper inclination of these openings, and in addition permits the necessary and desirable fullness between the leg openings as indicated at 14. It will be seen that 35 when the blank is formed in a generally oval contour the sides of the garment, as at 15 are provided with a desirable fullness, permitting the garment to be worn with comfort and without binding upon the 40 wearer.

From the foregoing it is obvious that my 45 invention is not to be restricted to the exact embodiment shown, but is broad enough to cover all structures coming within the scope of the annexed claims.

Having described my invention, what I claim is:

1. A garment formed from a flat blank, said blank being provided with leg openings

formed in the body of the blank and entirely within the outline of the same, said garment being seamless and formed by gathering or shirring the blank around its entire outer edge to produce a bag-like body. 50

2. A garment formed from a flat blank, 55 leg openings formed in said blank, means for contracting the entire outer edge of the blank to form the same into a bag-like garment, and expansible and contractible means at the leg openings. 60

3. A garment formed from a flat blank, substantially oval in contour, with leg openings formed within the outline of the blank, and at an angle to the longitudinal and transverse center lines thereof, means for 65 contracting the entire outer edge of the blank to form the same into a bag-like garment and expansible and contractible means at the leg openings. 70

4. A garment formed from a blank with 75 leg openings formed therein, said openings being disposed at an angle to and at one side of the longitudinal center line of the garment, the entire outer edge of said blank being shirred and provided with contractible and expansible means, shirring surrounding the leg openings and expansible and contractible means surrounding said leg openings. 75

5. A garment formed from a blank with 80 leg openings formed therein, said openings being disposed at an angle to the longitudinal center line of the blank, shirring at the edge of said blank to form the same into a bag-like garment, shirring surrounding the 85 leg openings, and a flat expansible strip secured over the inner side of the shirrings. 80

6. The process of forming a garment, comprising shirring an oval blank of material about its edge to produce a bag-like 90 garment, and shirring a pair of spaced apart leg openings therein, and providing an expansible and contractible means in the garment adjacent said shirrings. 90

Signed at the city of New York, county 95 of Queens, State of New York, this 16th day of September, 1919.

MARTIN ZWICKE.
